RELAY

Marvin G. Nelsen and Edward G. Baker, Chicago,
Ill., assignors to Guardian Electric Manufacturing Company, Chicago, Ill., a corporation of Illinois

Application December 26, 1939, Serial No. 311,007

10 Claims. (Cl. 200—87)

The present invention relates to relays, and more particularly to relays of the electro-magnetic type having a movable armature together with switch means connected in an electrical circuit to be controlled incident to the movement of the armature.

In most of the electro-magnetic relays of the general type referred to that have heretofore been designed and manufactured, the switch means for controlling an electrical circuit incident to the movement of the armature usually necessitates the use of a special mounting bracket associated with the field piece. Such construction results in a rather awkward unitary device of substantial size limiting its field of use, and which is relatively expensive to manufacture.

One of the objects of the present invention is to provide an improved form of electro-magnetic relay of the character indicated which is of relatively compact form, durable, positive in operation and capable of being manufactured for substantially less than equivalent devices heretofore marketed.

Another object is to provide an improved form of electro-magnetic relay of the type indicated which is characterized by the provision of a panel of insulating material rigidly attached to the upper end of the core in a manner to constitute a head for the coil, said panel also serving to provide a convenient mounting surface for the switching means to be actuated incident to the movement of the armature.

A further object is to provide an improved relay device of the character indicated wherein a panel of insulating material is rigidly attached to the upper end of the core in a manner to constitute a head for the coil and also serve as a convenient mounting for novel switch means of relatively simple form and which is capable of being easily assembled.

With these and other objects in view, our invention consists in the construction, arrangement and combination of the various parts of our device whereby the objects contemplated are attained, as hereinafter more fully set forth, pointed out in our claims and illustrated in the accompanying drawing, in which:

Figure 1 is a top plan view of a relay device embodying the present invention.

Figure 2 is a view part in section and part in elevation, taken substantially as indicated at line 2—2 of Figure 1.

Figure 3 is a view part in section and part in

15 elevation, taken substantially as indicated at line 3—3 of Figure 1.

Figure 4 is a top plan view of a relay device embodying a modified form of the present invention.

Figure 5 is a side elevational view of the relay shown in Figure 4.

10 Figure 6 is a view part in section and part in elevation, taken substantially as indicated at line 6—6 of Figure 4.

The electro-magnetic relay illustrated in Figures 1 to 3 of the drawing includes a stamped, metal field piece 10 of generally U-shaped formation, one leg of which, as indicated at 11, continues into an extension 12, bent inwardly above the field piece to serve as a stop for limiting the movement of the armature away from the core, as hereinafter described.

20 The upper portion of the leg 11 of the field piece is reduced and shouldered as indicated at 14 in Figure 3, to provide a seat or hinge mounting for an armature 16. Said armature is slotted and snugly fitted on said reduced portion of the leg 11 and includes a rearwardly extending portion 17 formed to provide an anchorage for one end of a coil spring 18, the lower end of which spring being attached to a lug 20 struck out of the lower portion of the upright leg 11 of the field piece. The extension 12 of the leg 11 is tapered as seen in the drawing, and the extreme end portion thereof is bent downwardly to a position to be encountered by the armature 16 at its uppermost position of adjustment, as seen in Figure 2, to which position it is yieldingly urged by the coil spring 18.

25 Rigidly mounted within the U-shaped field piece 10 on a seat of insulating material 22 is a coil 23 having a core 24, the upper end of which extends a substantial distance above the end of the coil 23. Mounted on said extended end of the core is a panel 26 of insulating material seated closely against the end of said coil 23 so as to constitute a head therefor. The panel is rigidly secured in position on the end of the coil by staking of the end of the core at a plurality of circumferentially spaced apart points, as indicated at 21. The panel 26 preferably includes a notched portion 26^a of U-shaped form to embrace the upright leg 11 of the field piece for assisting in maintaining the panel in fixed position.

30 The panel of insulating material in the construction illustrated is preferably of such dimensions as to provide portions 26^b projecting laterally beyond opposite sides of the armature 16.

These portions of the panel 26 provide convenient mountings for a dual set of switch means which, as illustrated, are similarly mounted on each of said panel portions 26^b. Said switch means each comprise a conductor finger 29 riveted to the upper side of said portion of the panel and a conductor finger 30 riveted to the underside of said portion of the panel in offset relation to finger 29, as may be seen in Figure 2. Said conductor fingers are dimensioned to extend 5 forwardly beyond the edge of the panel and are provided with cooperating contact buttons 29^a and 30^a, respectively, and the other ends of said conductor fingers are formed with terminals 29^b and 30^b, respectively, for connection to conductor wires of electrical circuits to be controlled. Each of the conductor fingers 30 include an extension 30^c at the forward end, projecting a substantial distance forwardly beyond the end of the corresponding conductor fingers 29, in position 10 to be engaged and actuated by a transversely extending bar 32 of insulating material rigidly attached to and projecting to opposite sides of the free end portion of the armature 16.

It is to be understood that the conductor fingers 30 are formed of resilient material and are normally biased in a direction with respect to corresponding conductor fingers 29 so as to dispose the contact buttons 29^a and 30^a in engagement with each other. It will therefore be apparent that when the coil 23 is deenergized the armature 16, under influence of spring 18, is caused to assume a position as seen in full lines in Figure 2 of the drawing with the contact buttons 29^a and 30^a of the respective switches in engagement to complete portions of electrical circuits to be controlled. When the coil is energized, the armature 16 is attracted to the core 24 as indicated in dot-and-dash lines in Figure 2, and the movement of the armature to such position causes the bar 32 to depress the extensions 30^c of the conductor fingers 30 to move said fingers against their biasing force for separating the contact buttons 30^a from their cooperating contact buttons 29^a.

While the switch means herein shown and described is shown in normally closed position when the armature is deenergized, manifestly said switch means may be modified so as to function in a manner opposite to that shown and described.

In the modified relay device illustrated in Figures 4 to 6 of the drawing, the field piece, coil, core and armature and certain other elements are substantially identical to corresponding elements of the construction above described and for convenience like parts in said Figures 4 to 6 are accorded the same reference characters as in Figures 1 to 3, together with the exponent "a."

In this construction a panel of insulating material indicated at 35 is secured to the core 24^a in the same manner as above described and includes a portion 35^a projecting laterally from one side of said armature 16^a. Mounted on said portion 35^a of the panel of insulating material is a switch device including conductor fingers 37 and 38 riveted in longitudinally offset relation to the upper and lower sides respectively of said portion 35^a of the panel of insulating material. Said conductor fingers are formed as stampings and are relatively rigid and each includes right angularly bent, spaced apart portions 37^a and 38^a disposed in substantial alignment with each other and extending in front of

75 and in spaced relation to the armature 16^a. Said conductor fingers are provided with extensions 37^b and 38^b respectively for connection to conductor wires in an electrical circuit to be controlled. Said bent portions 37^a and 38^a of the conductor fingers as may be seen in Figure 5 of the drawing, are bent downwardly in parallel spaced apart relation at an angle to the plane of the armature in either its attracted or released position. The ends of said angular portions 37^a and 38^a are provided with spaced apart contact buttons 37^c and 38^c respectively. Mounted on the armature 16^a in alignment with the contact buttons 37^c and 38^c is a conductor finger 39 of flexible material having a portion extending forwardly beyond the free end of the armature and bent downwardly at an angle to extend between the contact buttons 37^c, 38^c. Said conductor finger 39 is provided with a double contact button 39^a to alternately engage contact buttons 37^c and 38^c, by movement of the armature 16^a.

Due to the action of the coil spring 18^a, the armature 16^a is urged to its upper limit of movement when the coil 23^a is deenergized, disposing the contact button 39^a of conductor finger 39 in engagement with the contact button 37^c of switch finger 37. When the coil is energized and the armature 16^a is attracted to the core 24^a the conductor finger 39 moves downwardly with the armature and disposes its contact button 39^a in engagement with contact button 38^c.

Thus, the movement of the armature alternately controls portions of two different electrical circuits. The purpose of forming the conductor finger 39 of flexible material and disposing the bent portions 37^a and 38^a of the conductor fingers 37 and 38 respectively at an angle as above described is to permit double contact button 39^a to engage the contact buttons 37^c or 38^c in a wiping manner for assisting in maintaining the contacts clean and assuring positive completion of electrical circuit through said contacts.

45 In the construction illustrated in Figures 4 to 6 one end of the coil 23^a is connected by a conductor wire 40 to the conductor finger 39 on said armature. The other end of the coil as indicated by conductor wire 42 together with the terminals 37^b and 38^b may be connected in electrical circuits to be controlled by actuation of the armature of the relay.

The relay devices herein disclosed result in simplification of construction, reduced labor time in assembly, and provides a relatively compact device at substantially reduced cost as compared to the equivalent devices now available.

Although we have herein shown and described certain preferred embodiments of our invention, manifestly it is capable of further modification and rearrangement of parts without departing from the spirit and scope thereof. We do not, therefore, wish to be understood as limiting this invention to the precise embodiments herein disclosed, except as we may be so limited in the appended claims.

We claim as our invention:

1. A relay including a coil and a core, a field piece having an upright leg disposed adjacent the coil, an armature hingedly connected at one end to the leg of the field piece and disposed in registration with the end of the core, a relatively rigid panel of insulating material rigidly secured to the upper end of the core and constituting a head for the coil, said panel including

a portion projecting laterally beyond one side edge of the armature, and switch means adapted to be connected in an electrical circuit to be controlled incident to movement of the armature toward or away from the core, said switch means comprising a pair of conductor fingers rigidly attached at corresponding ends to opposite surfaces of the laterally projecting portion of said panel of insulating material, and having terminal portions for connection to conductor wires.

2. A relay including a coil and a core, a field piece having an upright leg disposed adjacent the coil, an armature hingedly connected at one end to the leg of the field piece and disposed in registration with the end of the core, a relatively rigid panel of insulating material rigidly secured to the upper end of the core and constituting a head for the coil, said panel including a portion projecting laterally beyond one side edge of the armature, and switch means adapted to be connected in an electrical circuit to be controlled incident to movement of the armature toward or away from the core, said switch means comprising a pair of conductor fingers rigidly attached at corresponding ends in longitudinally offset relation to the opposite surfaces of the laterally projecting portion of said panel of insulating material, and having terminal portions for connection to conductor wires.

3. A relay including a coil and a core, a field piece having an upright leg disposed adjacent the coil, an armature hingedly connected at one end to the leg of the field piece and disposed in registration with the end of the core, a relatively rigid panel of insulating material rigidly secured to the upper end of the core and constituting a head for the coil, said panel including a portion projecting laterally beyond one side edge of the armature, switch means mounted on said projecting portion of the panel of insulating material and adapted to be connected in an electrical circuit to be controlled incident to movement of the armature toward or away from the core, said switch means including a pair of switch fingers attached to opposite sides of said portion of the panel of insulating material and having corresponding ends projecting beyond the forward edge of said panel and provided with cooperating contact buttons, one of said fingers being yieldingly biased in one direction relatively to the other finger, and a member of insulating material secured to the free end of the armature in position to engage and move said yielding finger, in opposition to its biasing force, upon attraction of said armature toward said core.

4. A relay including a coil and a core, a field piece having an upright leg disposed adjacent the coil, an armature hingedly connected at one end to the leg of the field piece and disposed in registration with the end of the core, a relatively rigid panel of insulating material rigidly secured to the upper end of the core and constituting a head for the coil, said panel including portions extending laterally beyond opposite side edges of the armature, separate switches mounted on the respective laterally projecting portions of the panel of insulating material, each of said switches being adapted for connection in electrical circuits to be controlled, including a pair of fingers having cooperating contact buttons, one of said fingers of each switch being yieldingly biased in one direction relatively to the other finger, and a member of insulating material secured to the free end of the armature in position to engage and move said yielding fin-

gers, of the respective switches, in opposition to their biasing force upon attraction of the armature toward said core.

5. A relay including a coil and a core, a field piece having an upright leg disposed adjacent the coil, an armature hingedly connected at one end to the leg of the field piece and disposed in registration with the end of the core, a relatively rigid panel of insulating material rigidly secured to the upper end of the core and constituting a head for the coil, said panel including a portion extending laterally beyond one side edge of the armature, and switch means adapted to be connected in an electrical circuit to be controlled incident to movement of the armature toward and away from the core, said means comprising a pair of switch fingers connected to said portion of the panel and having spaced apart contact buttons, and a switch finger secured to and movable with said armature and disposed between said contact buttons, and normally in engagement with one of said contact buttons, said movable finger serving to alternately engage the contact buttons of the fingers of said pair for completing portions of electrical circuits, incident to movement of the armature.

6. A relay including a coil and a core, a field piece having an upright leg disposed adjacent the coil, an armature hingedly connected at one end to the leg of the field piece and disposed in registration with the end of the core, a relatively rigid panel of insulating material rigidly secured to the upper end of the core and constituting a head for the coil, said panel including a portion extending laterally beyond one side edge of the armature, and switch means adapted to be connected in an electrical circuit to be controlled incident to movement of the armature toward and away from the core, said means comprising a pair of switch fingers connected to opposite sides of said portion of the panel and having corresponding angularly bent spaced apart portions disposed beyond the outer end of the panel in front of the free end of the armature, contact buttons on each of said bent portions, and a switch finger secured to and movable with said armature and having an extension projecting between said contact buttons and normally in engagement with one of said buttons, said movable finger serving to alternately engage the contact buttons of the fingers of said pair for completing portions of electrical circuits, incident to movement of the armature.

7. A relay including a coil and a core, a field piece having an upright leg disposed adjacent the coil, an armature hingedly connected at one end to the leg of the field piece and disposed in registration with the end of the core, a relatively rigid panel of insulating material rigidly secured to the upper end of the core and constituting a head for the coil, said panel including a portion extending laterally beyond one side edge of the armature, and switch means adapted to be connected in an electrical circuit to be controlled incident to movement of the armature toward and away from the core, said means comprising a pair of rigid switch fingers connected to opposite sides of said portion of the panel and having corresponding angularly bent spaced apart portions disposed beyond the outer end of the panel in front of the free ends of the armature, contact buttons on each of said bent portions, and a flexible switch finger secured to and movable with said armature and having an ex-

tension projecting between said contact buttons and normally in engagement with one of said buttons, said movable finger serving to alternately engage the contact buttons of the finger of said pair for completing portions of electrical circuits, incident to movement of the armature.

8. A relay including a coil and a core, a field piece having an upright leg disposed adjacent the coil, an armature hingedly connected at one end to the leg of the field piece and disposed in registration with the end of the core, a relatively rigid panel of insulating material rigidly secured to the upper end of the core and constituting a head for the coil, said panel including a portion extending laterally beyond one side edge of the armature, and switch means adapted to be connected in an electrical circuit to be controlled incident to movement of the armature toward and away from the core, said means comprising a pair of switch fingers connected to opposite sides of said portion of the panel and having corresponding angularly bent spaced apart portions disposed beyond the outer end of the panel in front of the free end of the armature, said bent portions of the pair of switch fingers being disposed substantially parallel to each other at an angle to the plane of the armature at either its attracted or released position, contact buttons on each of said bent portions, and a switch finger secured to and movable with said armature and having an extension projecting between said contact buttons and normally in engagement with one of said buttons, said movable finger serving to alternately engage the contact buttons of the fingers of said pair for completing portions of electrical circuits, incident to movement of the armature.

9. A relay including a coil and a core, a field piece having an upright leg disposed adjacent the coil, an armature hingedly connected at one end to the leg of the field piece and disposed in registration with the end of the core, a relatively rigid panel of insulating material rigidly secured to the upper end of the core and constituting a head for the coil, said panel including a portion extending laterally beyond one side edge of the armature, and switch means adapted to be connected in an electrical circuit to be controlled incident to movement of the armature toward and away from the core, said means comprising a pair of switch fingers connected to opposite

sides of said portion of the panel and having corresponding angularly bent spaced apart portions disposed beyond the outer end of the panel in front of the free end of the armature, said bent portions of the pair of switch fingers being disposed substantially parallel to each other at an angle to the plane of the armature at either its attracted or released position, contact buttons on each of said bent portions, and a switch finger secured and movable with said armature and having an extension projecting at substantially the same angle as said bent portions between said contact buttons and normally in engagement with one of said buttons, said movable finger serving to alternately engage the contact buttons of the fingers of said pair for completing portions of electrical circuits, incident to movement of the armature.

10. A relay including a coil and a core, a field piece having an upright leg disposed adjacent the coil, an armature hingedly connected at one end to the leg of the field piece and disposed in registration with the end of the core, a relatively rigid panel of insulating material rigidly secured to the upper end of the core and constituting a head for the coil, said panel including a portion extending laterally beyond one side edge of the armature, and switch means adapted to be connected in an electrical circuit to be controlled incident to movement of the armature toward and away from the core, said means comprising a pair of rigid switch fingers connected to opposite sides of said portion of the panel and having corresponding angularly bent spaced apart portions disposed beyond the outer end of the panel in front of the free end of the armature, said bent portions of the pair of switch fingers being disposed substantially parallel to each other at an angle to the plane of the armature at either its attracted or released position, contact buttons on each of said bent portions, and a switch finger secured to and movable with said armature and having an extension projecting between said contact buttons and normally in engagement with one of said buttons, said movable finger serving to alternately engage the contact buttons of the fingers of said pair for completing portions of electrical circuits, incident to movement of the armature.
